UNITED STATES PATENT OFFICE.

GEORGE N. ROCK, OF BRANFORD, CONNECTICUT.

DESIGN FOR A GAME-BOARD OR SIMILAR ARTICLE.

40,915.

Specification for Design. Patented Sept. 27, 1910.

Application filed June 13, 1910. Serial No. 566,702. Term of patent 3½ years.

To all whom it may concern:

Be it known that I, GEORGE N. ROCK, a citizen of the United States, residing at Branford, in the county of New Haven and State of Connecticut, have invented a new, original, and ornamental design for a Game-Board or Similar Article; and I do hereby declare the accompanying drawing to be a full, clear, and exact illustration of the same, and which said drawing constitutes part of

this specification and represents a plan view of a game-board or similar article embodying my design.

Claim:

The ornamental design for a game board or similar article as shown.

GEORGE N. ROCK.
